UNITED STATES PATENT OFFICE

163,464

SET OF CHESSMEN

Ernest W. Logan, Wichita, Kans.

Application December 29, 1950, Serial No. 13,621

Term of patent 14 years

(Cl. D34—5)

To all whom it may concern:

Be it known that I, Ernest W. Logan, a citizen of the United States, residing at Wichita, State of Kansas, have invented a new, original, and ornamental Design for a Set of Chessmen, of which the following is a specification, reference being had to the accompanying drawings, forming a part hereof.

Figs. 1 to 4 inclusive are respectively front, rear, right hand side, and left hand side views of the king chessman, showing my new design;

Figs. 5 to 7 inclusive are respectively front, rear, and side views of a queen chessman, showing my new design;

Figs. 8 to 11 inclusive are respectively right hand side, rear, front, and left hand side views of a bishop chessman, showing my new design;

Figs. 12 to 14 inclusive are respectively front, rear, and side views of a knight chessman, showing my new design;

Figs. 15 to 17 inclusive are respectively front, side, and rear views of a castle or rook chessman, showing my new design; and

Figs. 18 to 20 inclusive are respectively front, side, and rear views of a pawn chessman, showing my new design.

Where only one side view of a chessman has been illustrated the other side is complementary and practically identical in appearance.

I claim:

The ornamental design for a set of chessmen, as shown and described.

ERNEST W. LOGAN.
